UNITED STATES PATENT OFFICE.

EDWARD H. SCHWARTZ, OF CHICAGO, ILLINOIS, ASSIGNOR TO EDWARD H. SCHWARTZ, INC., OF CHICAGO, ILLINOIS, A CORPORATION OF ILLINOIS.

BURNER.

1,391,416.

Specification of Letters Patent. Patented Sept. 20, 1921.

Application filed October 9, 1920. Serial No. 415,835.

To all whom it may concern:

Be it known that I, EDWARD H. SCHWARTZ, a citizen of the United States, residing at Chicago, in the county of Cook and State of Illinois, have invented a new and useful Improvement in Burners, of which the following is a specification.

This invention relates to fuel burners and is fully described in the following specification and shown in the accompanying drawing in which:

Figure 1 is a side elevation showing the furnace to which it is applied in section;

Fig. 2 is an end elevation of same;

Fig. 3 is an enlarged vertical section through the burner;

Fig. 4 is a horizontal section on the line 4 of Fig. 3;

Fig. 5 is an enlarged end view of the aspirating nozzle of Fig. 3; and,

Fig. 6 is an enlarged partial longitudinal section on the line 6 of Fig. 3.

The embodiment as illustrated is shown as applied to a furnace having a wall 10 to which is bolted a flange 11 in which is secured a hollow casting 12. A hollow member 13 is screwed into the casting 12 and has a partition 14 extending diagonally across the interior as shown in Fig. 4. Pipes 15 and 16 connect with each other through a coil 17 in the brickwork of the furnace wall and serve to connect the chambers formed on the two sides of the partition 14.

A hollow fitting 18 is secured to the member 13 and has a hollow casting 19 secured thereto, preferably with its axis at right angles to the members 12, 13 and 18. A tapered nozzle member 20 extends into the casting 19 and has a hollow fitting 21 secured at its outer end, the latter being closed by a cap 22. A tube 23 extends longitudinally of the members 19 and 21 and is screwed at one end into the cap 22 and is held at the other in the nozzle member 20.

This tube opens from the atmosphere into the mixing chamber 25 within the casting 19.

A hollow passage 26 surrounds the tube 23 and has a series of longitudinal orifices 27 opening into the mixing chamber 25, as shown in Figs. 3 and 5. The passage 26 is connected to any suitable source of steam or air supply by a pipe 28 and the pressure is controlled by the valve 29.

Air is introduced into the large chamber

30 in the casting 19 through one or more pipes 31 shown in Figs. 1 and 2. These may be connected to preheating coils similar to the coil 17 if desired.

The members 12, 13 and 18 are in axial alignment and the outer end of the T-shaped member 18 is closed by means of a screwed cap 32. A fuel nozzle 33 is screwed into a central opening in the cap 32 and extends centrally through the members 12, 13 and 18, the partition 14 in the member 13 having a central opening 34 which is closed by the fuel nozzle 33 and acts as a support therefor.

Referring now to Fig. 6 the discharge end 70 of the fuel nozzle 33 is closed by a plug 35 which has a central opening 36. This opening is controlled by means of a needle valve 37 having a stem 38 which is operable by means of the hand wheel 39 as shown in Fig. 3. The space 40 in front of the fuel nozzle is therefore a combustion chamber and this is surrounded by a hollow jacket 41 in the casting 12 to which liquid or gaseous fuel is supplied from any suitable source 80 through the pipe 42. The heated fuel then passes through the pipe 43 and thence through the fuel nozzle 33. The method of operation of this device is as follows:

When not in operation the valves 29 and 39 are closed. The valve 29 is first opened causing a supply of air or steam to be forced through the orifices 27 thereby inducing the flow of air to the tube 23 and the pipe 31. This mixture of air or air and steam as the case may be, passes through the narrow portion 25 and the member 18 into the pipe 15 as shown by the arrows in Fig. 4. This mixture then passes around through the coil 17 in the brickwork forming the side wall 95 of the furnace to which it is applied, and if the side wall is hot this mixture is highly preheated and returns through the pipe 16 on the opposite side of the partition 14 as shown by the arrows in Fig. 4. The valve 37 is then slightly opened by means of the hand-wheel 39 and fuel from the fuel nozzle 33 is preheated there and the combustible mixture is then ignited in the combustion chamber 40 in any suitable manner. Combustion begins in the combustion chamber 40 and continues through the opening 40* in the brickwork into the furnace to which it is applied.

When liquid fuel is used, it is highly pre- 110

heated and is sprayed into the combustion chamber 40 in the form of a gas or vapor which mixes readily with the preheated air and forms a combustible mixture which 5 burns readily and completely. When gaseous fuel is used, the gas is heated and expanded before mixing with the preheated air and the result to both cases is that a more efficient combustion and a hotter, cleaner fire 10 is obtained.

If desired, the casting 19 and parts carried thereby may be omitted and a blower or other means for supplying the air may be attached to the fitting 18.

15 While I have shown but a single embodiment of my invention, it is to be understood that it is capable of many modifications. Changes, therefore, in the construction and arrangement may be made which do not 20 part from the spirit and scope of the invention, as disclosed in the appended claims in which it is my intention to cover all novelty inherent in the invention as broadly as possible in view of the prior art.

25 What I claim as new and desire to secure by Letters Patent is:

1. A fuel burner having an air chamber and a mixing chamber separated by a partition, means for supplying air to said air 30 chamber, a hollow heating element surrounding said mixing chamber, piping leading from the air chamber to said heating element, piping leading from said heating element to said mixing chamber, and a fuel 35 nozzle adapted to spray fuel into the stream of preheated air.

2. A fuel burner comprising a hollow central portion having a transverse partition, means for supplying air to the hollow portion at one side of said partition, a hollow 40 heating element, piping leading from said hollow portion on one side of said partition to said heating element and back to said hollow portion on the opposite side of said partition and a fuel nozzle adapted to spray 45 fuel into this stream of preheated air.

3. A fuel burner, means for supplying air to the burner, a hollow heating element, piping leading from the burner to said heating element and back to said burner, a fuel 50 nozzle adapted to spray fuel into the stream of preheated air, a combustion chamber in which said combustion takes place, a jacket in said chamber in which the fuel is heated and means for carrying the fuel from said 55 jacket to the fuel nozzle.

4. A fuel burner comprising a hollow central portion having a transverse partition, means for supplying air to the hollow portion at one side of said partition, a hollow 60 heating element, piping leading from said hollow portion on one side of said partition to said heating element and back to said hollow portion on the opposite side of said partition, a fuel nozzle adapted to spray 65 fuel into this stream of preheated air, a combustion chamber in which said combustion takes place, a jacket in said chamber in which the fuel is heated and means for carrying the fuel from said jacket to the fuel 70 nozzle.

EDWARD H. SCHWARTZ.
